CLAIM

The ornamental design for a part of a hemostatic device, as shown and described.

DESCRIPTION

FIG. 1 is a perspective view of a part of a hemostatic device, showing our new design;

FIG. 2 is a front view thereof, the rear view being a mirror image thereof;

FIG. 3 is a right side view thereof;

FIG. 4 is a left side view thereof;

FIG. 5 is a top view thereof;

FIG. 6 is a bottom view thereof; and,

FIG. 7 is an enlarged cross-sectional end view taken along line 7-7 in FIG. 4.

The dash-dash broken lines showing portions of the part of a hemostatic device are for the purpose of illustrating environmental structure and form no part of the claimed design.

The dash-dot broken lines represent the boundary of the claimed design and no part of the claimed design.
